UNITED STATES PATENT OFFICE.

HENRY COLLIER SMITH, OF CAMBRIDGE, MASSACHUSETTS, ASSIGNOR TO SMITH-WARREN COMPANY, OF BOSTON, MASSACHUSETTS, A CORPORATION OF MASSACHUSETTS.

METALLIC WINDOW FRAME AND SASH.

SPECIFICATION forming part of Letters Patent No. 724,134, dated March 31, 1903.

Application filed January 2, 1902. Serial No. 88,227. (No model.)

To all whom it may concern:

Be it known that I, HENRY COLLIER SMITH, a citizen of the United States, residing at Cambridge, in the county of Middlesex and State of Massachusetts, have invented a new and useful Improvement in Metallic Window Frames and Sashes, of which the following is a full, clear, and exact description, reference being had to the accompanying drawings, forming a part of this specification, in explaining its nature.

The invention relates to an improvement in metal window frames and sashes, and particularly to means whereby the window-sashes may be combined with the frame to slide therein and may also be so combined with it as to be turned in the frame without being detached from the frame for the purpose of rendering both sides of the sash accessible from the same place.

I will now describe the invention in connection with the drawings forming a part of this specification, wherein—

Figure 1 is a view, part in elevation and part in vertical section, of enough of a window-frame and window-sashes to illustrate the invention. Fig. 2 is a detail view, enlarged, representing a means for locking the sashes together. Fig. 3 is a view in section upon the dotted line 3'3' of Fig. 2. Fig. 4 is a view in horizontal section upon the dotted line 4'4' of Fig. 2 and in plan of parts below said line. Fig. 5 is a view in horizontal section upon the dotted line 5'5' of Fig. 1. Fig. 6 is a view in horizontal section upon the dotted line 6'6' of Fig. 1. Fig. 7 is a view in horizontal section upon the dotted line 7'7' of Fig. 1. Fig. 8 is a view of the parts in Fig. 7, representing them in a different position. Fig. 9 is a view in elevation, representing a form of spring-holder to which reference will hereinafter be made. Figs. 10 and 11 represent a modified construction of side extension and trunnions, Fig. 10 being a vertical section on the line 10'10' of Fig. 11.

Referring to the drawings, the upper window-sash A and the lower window-sash B slide in recesses in the sides of the window-frame C. They are in part balanced by

weights connected with them by chains, the lower sash being enough heavier than its weights to close upon the release of holding-shoes, to be described, and the upper sash being enough lighter than its weights to be closed by them upon the release of corresponding holding-shoes.

Any suitable form of frame may be employed which is provided with guiding-recesses of a character to receive the sashes and their trunnions. In Fig. 5 I have represented the frame as having recesses c and recesses c' for the trunnions. In Figs. 10 and 11 the frame shown has the same provision, the difference being that the recess for the trunnion is as wide as the recess for the sash and in extension of it.

The sash that I prefer to use has extension sides movable toward and from the remainder of the sash into and out of recesses in the frame in which they normally are for the usual sliding operation of the windows. These extensions provide means whereby the sashes may be placed in the window-frame and entirely removed therefrom without making any portion of the window-frame detachable. The extensions also slide upon the trunnions.

D represents the extensions, and E the trunnions. The extensions are movable in relation to the main frame of the sash in any desired way, and I have shown them in Figs. 5 and 9 as movable telescopically with relation thereto without having endwise movement, while in Figs. 10 and 11 a slight endwise movement is provided them. The first-named construction requires the use of means passing through the sash by which the sides may be reached and moved, which the modification of Figs. 10 and 11 avoids.

d represents the means for moving the extensions. It is in the form of a latch bar or rod extending through a hole in the sash, having an exposed end or handle d'. Its inner end d'' is contained in the cavity of the sash-frame and is connected with the extension by an adjusting-screw d'', which permits of a variable relation between the bar or rod and the extension. Each extension may have two or more of them, and each has a latch d' (see

Fig. 1) to engage the catch d^5 on the sash when the extension has reached the limit of its outward movement. By moving them in one direction the extension is moved inward 5 toward the remainder of the sash, and by moving them in the other direction the extension is moved into the recess in the frame. In Figs. 10 and 11 the extensions are represented as provided with inclined slots d^7 , 10 through which cross-rod d^8 , attached to the fixed section of the sash-frame, extend. By sliding the extensions lengthwise the fixed section of the sash they will also be at the same time moved inward or outward with inclined edgewise movement. It will thus be 15 noted that the sash extensions of Figs. 10 and 11 are moved lengthwise the window-sashes as well as toward and from them and that when withdrawn to free the sashes from the 20 slides they extend below the bottom of the lower sash and above the top of the upper sash. Consequently when it is desired to re-engage the sashes with the slides it is simply necessary to bring them in line with the slides 25 and then move them to the bottom or top of the frame, as the case may be, when the ends of the extensions coming into contact with the bottom or top of the frame will be moved outward automatically into the sideways with 30 a lateral drawing motion, and the engagement of the sashes with the frame will thus take place. The movement of the extension, however, does not cause the movement of the trunnions or pivots E. These trunnions ex- 35 tend through holes in the extension, which are slots where the extension has the construction of Figs. 10 and 11, and are rigidly secured to the fixed part of the window-sash, I prefer to the part d^6 of the sash, which forms 40 the recess for receiving the edge of the glass, and I also prefer that the trunnion be shaped to straddle this part and be secured thereto by riveting or in any other desired way.

The outer ends of the pivots or trunnions 45 fit the recesses in the frame which contain them and may be of any desired length, and I prefer that the pivots or trunnions carry or support the friction or holding shoes F, which by bearing against the window-frame serve 50 to hold the sashes to any position to which they may be opened as against the tendency of the lower sash to close or of the weight to close the upper sash. The shoe has a flat end of about the width of the trunnion and to fit 55 the recess in which the trunnion slides. It is mounted upon the end of a rod f, extending into a longitudinal hole in the trunnion or pivot made to receive it, and its inner end extends into a slot f' across the pivot or trunnion. It is frictionally held against the window-frame by the spring-rod f'', contained in the cavity of the window-sash, and provided with the bent end f'', where it is united by 60 fusible solder to the window-sash near an opening therein, so that heat from without the sash may at once reach it. The rod f'' is held

in position to obtain a bearing against the end of the holding-rod by the clip f''. This clip is held in adjustable position by means of the bolt f', so that the clip, and so the rod f'' held thereby, may be moved laterally and its tension upon the end of the holding-rod f varied at will. This result is secured by providing the clip with a threaded hole, as may be obtained from the fixed nut f'', into which 75 screws the bolt f', accessible from without the sash, but which by its headed end f''' contained in the block f'', is so held to the side of the sash that the bolt may be turned by suitable means, but prevented from being 80 turned in and out. The result is that the clip moves back and forth upon the bolt f', and so produces a lateral adjustment of the rod f'', resulting in an increased or diminished 85 tensional bearing upon the end of the holding-rod f, supporting the friction bearing-shoe. As may be seen from Fig. 9, the rod f'' has an offset at the point f'', so that the upper section of the rod which bears against the 90 holding-rod is away from the center of the lower section of the rod attached to the sash and passing through the clip f' as a center. Upon a release of the rod where it is soldered to the sash at f'', as in case of fire, the rod 95 turns sufficiently in the clip f' as a center that its upper section swings away from the end of the holding-rod, and the tension resulting being removed from the friction bearing-shoe the window, being overbalanced, as before described, automatically closes.

To place the sashes in the window-frame, their extensions are moved inward against the fixed sections, leaving exposed the ends 105 of the trunnions or pivots and the friction bearing-shoes issuing therefrom and in their engaging position. The sash cords or chains F' are then attached to the ends of the trunnions, as may be seen by reference to the 110 drawings. The trunnion or pivot and its friction bearing-shoe on one side of the sash is then placed in its recess in the frame, the sash turned to a horizontal position and lifted on the said trunnion or pivot as a center until the disengaged trunnion may clear the frame and enter its recess on the other side of the frame, when the sash is turned in a horizontal position and then turned to a vertical position, which will bring its extensions 115 in line with their holding-recesses in the frame. The extensions are then moved outward into them, and the sash is free to be moved vertically in the frame. It is to be observed that after the two trunnions have 120 entered their recesses and the friction-shoes brought to bear against the side of the frame the sash will be sustained and its pivoting in being brought from a horizontal to a vertical position easily obtained. The attachment of the sash-chains to the ends of the trunnions and the method before described 125

for increasing the tension upon the friction bearing-shoes are also to be noted as facilitating this adjustment.

To turn the sash in the frame, it is simply necessary to move inward the extensions. The friction bearing-shoes will remain in their bearing against the sides of the frame and the ends of the trunnions to which are attached the sash-chains left exposed. The sash may then be turned to expose either surface to the inside of the window without becoming disengaged from the frame and without engaging with the sash-chains or interfering with the stress of the shoes upon the frame, which prevents the sash from operating the sash-weights or the sash-weights operating the sash while it is thus being manipulated.

It will be understood from the foregoing that the friction bearing-shoes are automatically released by heat and that when so released the sashes automatically close. They are automatically locked when closed by the latch G, which is pivoted to the upper-sash frame to engage by gravity a shoulder or catch g upon the lower sash when it has been moved by it. (See Fig. 3.) This latch is described in another application of even date and is not claimed herein.

The sashes have weather-stops provided in their meeting-rails by means of the overlapping plate h, secured to the meeting-rail H of the lower sash, and the overlapping plate h', secured to the meeting-rail H' of the upper sash. These plates each provide a recess into which the opposing plate may enter, and thus provide an overlapping weather-lock, doing away with any necessity for a wedging of the rails together and the use of a wedge in connection with the sash-lock, as described in my said application. The plate h is united to the plate h² and the meeting-rail H by extending along its side underneath it, then upward into the glass-retaining recess, forming one wall of it, and then downward over an upturned flange of the said plate h². This construction serves also to stiffen and strengthen the rail H. The overlapping plate h' is formed from extensions of the plates h³ of the meeting-rail H', which are bent outward together, then upward together, one of them being made sufficiently long to be bent downward over the edge of the other.

The movable extensions D of the window-sash may be combined with the rigid part of the sash-frame in any desired way to be movable toward and from it for the purpose of widening it. The form of construction which I prefer to employ is represented in Figs. 10 and 11, where the extension D on one side of the sash-frame is represented as made from one piece of sheet metal so bent as to provide the deep side recess d⁹ substantially in line with the sides of the recess in the window-frame. Into these recesses extend the sections d¹⁰ of the fixed part of the sash-frame. This is preferably made of one piece of sheet

metal formed to provide the groove d¹¹ for the glass and the sides d¹² d¹³ and the outer faces d¹⁴ d¹⁵ at each side of the recess or slideway 70 in the window-frame; the sections d¹⁰ engaging the movable extension, which forms the walls of a space between the sides and which space is of the width of the recess or slideway 75 in the window-frame. The sections d¹⁰ are wide and the recesses d⁹ are deep and the space within the sash-frame beyond the extensions of sufficient depth to permit the extension D to be moved into the sash without disengaging the parts, the extension sliding 80 upon the sections d¹⁰ and the movement being sufficient to bring the outer edge of the extension in line with the outer faces d¹⁴ d¹⁵. The parts of the extension forming the recesses d¹⁰ are slotted to permit the movement 85 of the extension with respect to the cross-rods d⁸, and these slots are inclined where it is desired to effect the closing or opening of the extension by its own movement lengthwise the window-sash. Each extension D also has 90 in its outer face a recess d¹⁶ for receiving a part of the trunnion and shoe (see Fig. 11) and also to provide room for the sash-holding cord or chain which engages the trunnion.

To increase the frictional surface of the 95 brake-shoe, it may be slightly beveled, as represented in Fig. 11, and the surface of the window-frame against which it bears may be correspondingly shaped.

In Figs. 5, 6, 7, and 8 the extension E and 100 the sash-rail are somewhat differently constructed, the extension being reinforced upon its sides by portions of the plate forming it, which are bent backward directly, entering deep recesses in the sash-rail formed by inward and outward extending parts of the rail, the inward-extending part serving to reinforce the sides of the rail. I do not, however, confine myself to any particular way of attaching the side extensions to the sash-rails, 105 so that they may be moved bodily toward and from the sash-rails.

In use the window-sashes are arranged to close in the ordinary way and, if open, in case of fire in their vicinity releasing their thermostatic holders, close automatically. The sashes are placed in their window-frames as I have already described.

It is to be observed that the construction is especially advantageous in the washing or 110 cleaning of the windows, in that the outer surface of the window may be cleaned from inside the room, and this without the removal of any part. This may be done simply by moving inward the extensions, when the sash 115 may be revolved to any position of advantage. During this manipulation the sash is held to the side of the frame by the friction bearing-shoes, upon the holding-rods of which the trunnions turn for a center. Where the thermostatic release is employed, the friction bearing-shoes will still be held to the frame by sufficient friction to hold the sash, and this 120 by a means which in no way interferes with

the normal bearing of the shoes or the manipulation of the sash. The sashes are restored to their original positions in the window-frame by being moved to a vertical position with respect thereto and by moving out the extensions, as before explained.

Having thus fully described my invention, I claim and desire to secure by Letters Patent of the United States—

1. A metal window-frame having sash holding and guiding recesses, a window-sash having side-rail extensions vertically and rotatably movable therewith, and laterally movable with relation thereto, that they may be drawn out into the said recesses within the frame to guide the sash during its sliding vertical movement, and withdrawn from said recesses in order that the sash may pivot, and means for the support of the sash when pivoting.
2. A metal window-frame having sash holding and guiding recesses, a window-sash having side-rail extensions vertically and rotatably movable therewith, and laterally movable with relation thereto, that they may be drawn out into the said recesses within the frame to guide the sash during its sliding vertical movement, and be withdrawn to permit of the sash pivoting, means for the support of the sash when pivoting, and means for the adjustment of the sash when sliding, substantially as described.
3. A metal window-frame having sash holding and guiding recesses, a window-sash having side-rail extensions vertically and rotatably movable therewith, and laterally movable with relation thereto, that they may be drawn out into the said recesses of the frame to guide the sash during its sliding movement, and be withdrawn to permit of the sash pivoting crosswise the frame, trunnions attached to, and extending from the sash into said recesses, window-weights out of balance with the sash connected with the said trunnions, and means for frictionally holding the trunnions to the window-frame substantially as described.
4. A metal window-frame having sash holding and guiding recesses, a window-sash, trunnions extending from the sash into said recesses, side-rail extensions movable into and from said recesses, window-weights out of balance with the sash, devices frictionally connecting the trunnions with the window-frame, and means actuated by heat for releasing said frictional devices.
5. A metal window-frame having sash holding and guiding recesses, a window-sash, trunnions extending from the sash into said recesses, window-weights connected therewith, side-rail extensions movable into and from said recesses having recesses upon their faces for holding the trunnions and weight connections.

6. A metal window-frame having sash holding and guiding recesses, a window-sash having side-rail extensions vertically and rotatably movable therewith, and laterally movable

with relation thereto, that they may be drawn out into the said recesses within the frame to guide the sash during its sliding movement 70 and withdrawn to permit of its pivoting crosswise the frame, trunnions extending from the sash into the said recesses, means for holding said trunnions, means for obtaining a movable support for said trunnions along the 75 sides of the frame, and means for moving said side-rail extensions as aforesaid without moving the trunnions.

7. A metal window-frame having sash holding and guiding recesses, a window-sash, trunnions extending from the sash into said recesses, side-rail extensions movable into and from said recesses, means for moving said extensions from said recesses, and means for locking said extensions to the window-sash 85 when in said recesses.

8. A metal window-frame having sash holding and guiding recesses, an upper and lower window-sash, trunnions upon each extending into said recesses, weights out of balance with 90 said sashes, the lower sash being heavier than its weights and the upper sash lighter than its weights, side-rail extensions upon each sash movable into and from said recesses, frictional devices carried by the trunnions to 95 bear against the window-sashes and hold them against a tendency to close, and means actuated by heat for releasing said frictional devices, thus permitting the lower sash to overbalance its weights and the weights of 100 the upper sash to close it.

9. A metal window-frame having a sash holding and guiding recess, an upper window-sash and lower window-sash, the meeting-rails of which have a weather-stop concealed between the meeting-rails of the sashes and consisting of the weather-stop extending from and forming a recess along the outer side of the upper rail of the lower sash and the tongue extending up through and alongside 110 the inner side of the lower rail to the upper sash and adapted to enter said recess substantially as described.

10. A metal window-frame having sash holding and guiding recesses, a window-sash, 115 trunnions having fixed relation to and extending from the sash into said recesses, shoes carried by said trunnions to bear against the window-frame and movable thereon, and a yielding shoe-holder.

11. A metal window-frame having sash holding and guiding recesses, a window-sash, trunnions extending from the sash into said recesses, shoes carried by said trunnions to bear against the window-frame and movable 125 thereon, a yielding shoe-holder and means for releasing the holder actuated by heat.

12. A metal window-frame having sash holding and guiding recesses, a window-sash, trunnions extending from the sash into said recesses, shoes carried by said trunnions to bear against the window-frame and movable thereon, a yielding shoe-holder, and means for adjusting the holder.

13. A metal window-frame having sash holding and guiding recesses, a window-sash made of sheet metal shaped to form a glass-receiving recess, trunnions fastened at their inner ends to the sash at each side of said recesses, to strengthen the sash at said point, and extending through movable sides of said sash into the recesses, the said window-frame, and said movable sides.
14. A metal window-frame having sash holding and guiding recesses, a window-sash shaped from sheet metal to provide a glass-holding recess, side faces d^{14} , d^{15} , and inward-extending sections d^9 , d^{10} , side-rail extensions formed from sheet metal and having deep recesses formed by sections thereof which overlap the sections d^{10} , apertures in said extensions, trunnions fastened to the sash and extending through said apertures into the window-frame recesses, and means combining the extensions with the sash whereby longitudinal movements of the extensions will cause them to be at the same time moved inward or outward from the sash-frame.
15. A metal window-frame having sash holding and guiding recesses, a window-sash, trunnions extending from the sash into said recesses having at their outer ends means for receiving window-weight connections and also having a longitudinal hole opening into a vertical slot, a frictional shoe carried by said trunnion having a shank to extend through the hole therein to said slot and a yielding holder extending through said slot to bear against the said shank.
16. A metal window-frame having sash holding and guiding recesses, a window-sash, trunnions extending from the sash into said recesses narrower than said recesses, means for steadyng said trunnions within said recesses, and side-rail extensions wider than said trunnions movable into and from said recesses.
17. The combination of a metal window-frame having sash holding and guiding recesses, a window-sash, trunnions extending from the sash into said recesses and having a fixed relation to the sash, window-weights attached to the trunnions within said recesses, sliding frictional devices carried by the trunnions and frictionally combining them with the window-frame, means actuated by heat for automatically releasing said frictional devices from contact with the walls of the recesses, and movable bearings connecting the window-sash with the window-frame.
18. A metal window-frame having sash holding and guiding recesses, a window-sash having side-rail extensions vertically and rotatably movable therewith, and laterally movable with relation thereto, that they may be drawn out into the said recesses within the frame, to support the sash during its sliding vertical movement, and withdrawn from said recesses to permit of its pivoting, trunnions having a fixed relation to the sash and extending from said sash into said recesses, window-weights attached to the trunnions for supporting the same, sliding frictional devices carried by the trunnions and frictionally combining them with the window-frame, substantially as described.
19. A window-sash having an adjustable side rail, the same consisting of a fixed section permanently secured to the top and bottom rails of the sash, a movable section fitting into said permanent section and horizontally movable with relation thereto, so increasing or diminishing the width of the sash, and means whereby the movable section may be moved out with lateral drawing motion, substantially as described.
20. A sheet-metal window-sash having an adjustable side rail, the same consisting of a fixed section permanently secured to the top and bottom rails of the sash and being so formed as to provide a relatively deep recess along its outer edge, a movable section fitting into the recess aforesaid and forming with the permanent section a telescopic joint, permitting of the movable section being moved in and out without disengagement, cross-rods for the retention of said movable section and inclined, slotted openings within the sides of said movable section that it may be moved out upon the cross-rods with a lateral drawing motion, substantially as and for the purposes set forth.

HENRY COLLIER SMITH.
